RAILWAY TRAFFIC CONTROLLING APPARATUS WITH MANUAL CHANGE-OVER FROM REMOTE TO LOCAL CONTROL

Thomas W. Hays, Salt Lake City, Utah, assignor to The Union Switch and Signal Company, Swissvale, Pa., a corporation of Pennsylvania

Application September 12, 1944, Serial No. 553,689

6 Claims. (Cl. 246—3)

1

My invention relates to railway traffic controlling apparatus, and more particularly to centralized traffic control systems for single track railways.

In systems of this character it is the practice to govern the operation of the track switches and the clearing of the signals in accordance with traffic conditions by a system of trackway circuits controlled by track relays, upon which manual control is superimposed by the operation of a suitable communication system, usually of the code type. Since train movements over the single track are permissible in only one direction at a time, the signals for both directions are usually controlled over the same circuits. This is made possible by the provision of means for setting up the desired direction of traffic through the various blocks and for clearing the signals in accordance with the condition of the blocks by the transmission of suitable codes of impulses from the point of control, which usually is the train dispatcher's office. In the event of an accident to the communication system of such a nature as to render it inoperative, it is ordinarily necessary to operate trains by a system of train orders and to either take the signal system entirely out of service or to provide local operators at the way stations.

The principal object of my invention is to provide emergency means for restoring the signal system to service under the condition mentioned, by converting it to an automatic block system of the absolute permissive type, in which the signals normally stand at clear for both directions. This is accomplished by the provision of manual switching means, comprising a two-way multiple contact switch or circuit connector at each signal location, by which all the circuit changes required at a location for conversion from centralized control to automatic block operation may be made at one time without error.

Under centralized operation but one pair of line wires are required for the control of the signals governing traffic through the single track blocks, since the circuits are energized in only one direction at a time. Under automatic block operation an additional line circuit is needed to provide circuits for both directions, and this is obtained in accordance with my invention by using the line wires of the code communication system which otherwise would be idle. A feature of my invention is the provision of means for extending the control limits of the signals by means of the adjustable connectors mentioned to provide the proper protection for opposing

2

train movements under automatic block operation, in which longer blocks are necessary than under centralized operation in which the signals for one direction or the other stand normally at stop.

Under automatic signal operation, circuits for the power operated track switches of the centralized traffic control system are arranged in such a manner as to adapt the switches to hand operation, "dual control" power switch machines being provided as is the practice in centralized traffic control systems. A feature of my invention is the provision of time locking means for controlling the signals governing movements out of the side tracks under automatic operation employing apparatus which operates in a different manner under centralized operation.

I shall describe one form of apparatus embodying my invention, and shall then point out the novel features thereof in claims.

Referring to the accompanying drawings, Figs. 1A, 1B and 1C when arranged side by side with Fig. 1A at the left, show the track plan for the single track block extending between two passing sidings, together with the trackway circuits for one form of apparatus embodying my invention. More particularly, Figs. 1A and 1C show the apparatus at the two field stations of the centralized traffic control system located at the opposite ends of the single track block, including circuits for the control of the power operated track switches 1W and 7W, respectively, and for the associated entering and leaving head block signals. These signals are identified by the reference characters 2 and 8, respectively, with a suffix R or L designating the right-hand or left-hand direction and an additional suffix A when the signal governs main line train movements or the suffix B when the signal governs movements into or out of the siding. Fig. 1B shows the circuits for a pair of intermediate signals 3 and 4 and also for a second pair 5 and 6 at spaced locations within the single track stretch.

It is to be understood that the system is made up of unit portions similar to those shown. The circuits extending to the right-hand margin of Fig. 1C match those extending to the left-hand margin of Fig. 1A so that Figs. 1C and 1A, with Fig. 1C at the left, together illustrate the circuits for the signals governing movements over the main track of the double track stretch including the siding.

Similar reference characters refer to similar parts in each of the views.

The centralized traffic control system to which

my invention is applied is generally similar to that disclosed in a pending application for Letters Patent of the United States, Serial No. 501,254, filed September 4, 1943, by Henry S. Young, for Railway traffic controlling apparatus. A detailed consideration of the communication system by which the system is manually governed from a central office is not needed for an understanding of my invention, and it is deemed sufficient to point out that this is of the general type shown in Letters Patent of the United States No. 2,197,130, issued April 16, 1940, to Lloyd V. Lewis, for Remote controlling apparatus, and comprises a plurality of coding units at a control office, not shown, and one at each field station as indicated by the reference characters U1 and U2 in Figs. 1A and 1C. The office and station coding units are connected by a circuit including a pair of line wires Y1 and Z1 which extend from the office through each station in turn over which indication codes are transmitted in response to changes in trackway conditions to indicate the condition of the station apparatus at the office. Control codes are also transmitted by the office coding unit at times over the same line wires by means of which the operator at the control office is enabled to operate a group of control relays at a selected station to impose manual control upon the trackway apparatus. As shown in Fig. 1A, the code controlled relays include a switch control relay 1WS for governing a power switch machine 1SM for the track switch 1W, two signal control relays 2RHS and 2LHS for controlling a left or right-hand signal selected in accordance with the position of switch 1W, and a traffic direction control relay 2RFS. It is to be understood that each of these relays is of the polar stick type and is operable to close its left-hand or right-hand contacts in response to a code received from the office by the coding unit U1.

The station shown in Fig. 1C includes a similar group of control relays 7WS, 8LHS, 8RHS and 8LFS, which are controlled by the coding unit U2. The traffic relays 2RFS and 8LFS jointly control the direction of energization of a two wire reversible line circuit system which extends the length of the single track block, by means of which the signals are controlled in accordance with traffic conditions as manifested by track relays, continuous track circuits being provided as shown.

As disclosed herein, the switching arrangements embodying my invention comprise groups of adjustable connectors such as the connectors 11 to 29, inclusive, in Fig. 1A and connectors 31 to 40, inclusive, in Fig. 1B. Each connector consists of three spaced terminal posts and an adjustable copper strap by means of which each middle post may be connected either to its right-hand post, as shown, for normal centralized operation, or to its left-hand post, for emergency operation. All of the connector straps of a group are permanently connected together by means of a strip of insulating material as indicated in order to facilitate changing all of the connectors at one time without error.

It will be seen that the connector straps 11 and 12 in Fig. 1A, straps 31 and 32 at the location of signals 3 and 4 in Fig. 1B, straps 51 and 52 at the location of signals 5 and 6 in Fig. 1B, and straps 71 and 72 in Fig. 1C are normally connected in series with the line wires Y1 and Z1 of the communication system to provide a through line circuit for the coding units U, which circuit extends

through each field station to the control office, as already pointed out.

In describing my invention I shall first explain the operation of the line circuit system under normal conditions with the connector straps all in their right-hand positions as shown, and I shall then describe the line circuits as they are arranged under the emergency condition when the connector straps occupy their left-hand positions, and finally, I shall trace the local circuits for controlling the signals and track switches at the head block locations under the two conditions.

Under centralized operation, the two traffic relays 2RFS and 8LFS at the opposite ends of the single track block are operated to similar positions by codes transmitted from the control office and selectively received by the coding units U1 and U2, and as shown, the right-hand contacts of the traffic relays are closed, in which case the system is set for traffic movements from left to right and the line wires 41 and 42, 43 and 44, 45 and 46 are each energized by connections to the terminals B and C of suitable local sources of current.

If sections 6T, 7T and 8T are unoccupied, the current supplied to the line wires 41 and 42 energizes a polarized line relay 6HD, controlling signal 6, Fig. 1B, the circuit being completed through relay 6HD over connectors 54 and 57, back contacts *a* and *b* of the similar relay 5HD for signal 5, back contacts *b* and *d* of a directional stick relay 5S associated with relay 5HD, connector 56, the winding of an approach relay 5AR, contacts *a* and *b* of the track relay 6TR for section 6T, line wires 41 and 42, contacts *a* and *b* of the track relay 8TR, connectors 74 and 75, the right-hand contacts *a* and *b* of relay 8LFS, contact *b* of an approach locking relay 8LAS controlled by the opposing signals 8LA and 8LB, contacts *a* and *b* of a pole changer relay 8RPC controlled by signal 8RA, and thence to terminal C, and to terminal B at contact *a* of relay 7TP through the winding of an approach relay 8RAR, relay 7TP being a repeater of the track relay 7TR for the switch section 7T.

The head block signals, such as the signals 2RA, 2RB, 8RA and 8RB, or 2LA, 2LB, 8LA and 8LB, are of the well-known searchlight type each having a mechanism including a lamp and a circuit controller as shown in Figs. 1A and 3A. When the signal lamp is lighted the signal displays a red or stop indication if deenergized, and displays a yellow caution or a green proceed indication when energized in one direction or the other as indicated by the letters G and Y on the drawing.

The intermediate signals of Fig. 1B are of the color light type having three lamps for displaying corresponding indications as indicated by the letters G, Y and R, the lamps being controlled over the contacts *d* and *e* of the associated line relay HD.

The polarity of the current supplied over line wires 41 and 42 is normally such as to condition signal 6 to indicate caution, but when signal 8RA in advance indicates proceed, relay 8RPC becomes energized to reverse the polarity of the current supplied to relay 6HD to cause signal 6 to indicate proceed.

The signals are normally dark, and as shown typically by the lighting circuit for signal 5 or for signals 2RA and 2RB, for example, an approach relay such as relay 5AR or relay 8RAR connected in series in the line circuit including wires 41 and 42 releases when the block section in approach to the signal is occupied, and relay 8RAR releases a repeating relay 8RAP. Relay 5AR, by closing its

back contact *a* causes the lamp of signal 5 to become lighted, and the closing of back contacts *a* and *b* of relay 8RAP causes the lamps of signals 8RA and 8RB to become lighted.

When relay 6HD is energized, its front contacts *a* and *b* connect terminals B and C of the adjacent local source of current to the right-hand end of the circuit including the line wires 43 and 44, over which the similar line relay 4HD for signal 4 is energized, provided sections 4T, 5T and 6T are unoccupied. This circuit extends from the terminals of relay 4HD over connectors 39 and 40, back contacts *a* and *b* of relay 3HD, back contacts *b* and *d* of relay 3S, connector 38 and the winding of relay 3AR, contacts *a* and *b* of relay 4TR, line wires 43 and 44, contacts *a* and *b* of relay 5TR, the winding of relay 6AR and connector 59, back contacts *b* and *d* of relay 6S, front contacts *a* and *b* of relay 6HD to terminal C, and to terminal B at front contact *c* of relay 6TR, the polarity being such as to cause signal 4 to indicate proceed when relay 6HD is energized.

Each intermediate signal is provided with a directional relay such as the relay 6S. When relay 6HD is energized, the release of relay 5TR by a train moving from left to right and approaching signal 6 completes a circuit at back contact *c* of relay 5TR to pick up relay 6S. Relay 6HD is released by relay 6TR when the train enters section 6T, completing a stick circuit for relay 6S extending to terminal B at back contact *c* of relay 6HD. Then when the train vacates section 6T, current is supplied from terminals C and B to line wires 43 and 44 over front contacts *b* and *d* of relay 6S and front contact *c* of relay 6TR to energize relay 4HD in the reverse direction to condition signal 4 to indicate caution.

When relay 4HD is energized, its front contacts *a* and *b* connect terminals B and C at connectors 33 and 35 to the right-hand end of the section of the line circuit system which includes the line wires 45 and 46. If sections 2T and 3T are vacant, current is supplied over line wires 45 and 46 to energize the line relay 2RHD, Fig. 1A, the circuit being completed through the winding of relay 2RHD over the right-hand contacts *a* and *b* of relay 2RFS, connectors 14 and 15, contacts *a* and *b* of relay 2TR, line wires 45 and 46, contacts *a* and *b* of relay 3TR, the winding of relay 4AR, and connector 36, back contacts *b* and *d* of relay 4S, front contacts *a* and *b* of relay 4HD to terminals B and C at connectors 33 and 35, the polarity of the current being such as to cause signal 2RA to indicate proceed when relay 4HD is energized and to indicate caution when relay 4S is energized, provided switch 1W is normal. When switch 1W is reversed, relay 2RHD energizes signal 2RB over its neutral contacts to indicate caution irrespective of the line polarity.

To set up the right to left traffic direction, the relays 2RFS and 8LFS are both operated to their left-hand positions by code control, thereby de-energizing the line circuits just traced and establishing others which are oppositely directed but similar and which include the same line wires. If signals 2RA and 2RB are at stop and the associated approach locking relay 2RAS and relays 1TP, 2TR and 3TR are energized, relay 3HD is energized over the circuit extending from its winding over connectors 34 and 37, back contacts *a* and *b* of relay 4HD, back contacts *b* and *d* of relay 4S, the winding of relay 4AR and connector 36, contacts *a* and *b* of relay 3TR, line wires 45 and 46, contacts *a* and *b* of relay 2TR, connectors 14 and 15, the left-hand contacts *a* and *b*

of relay 2RFS, contact *b* of an approach locking relay 2RAS, controlled by signals 2RA and 2RB, contacts *a* and *b* of the pole changer relay 2LPC for signal 2LA, to terminal C, and through relay 2LAR to terminal B at contact *a* of relay 1TP.

- Relays 5HD and 8LHD have energizing circuits similar to those for relays 4HD and 2RHD already traced. The circuit for relay 5HD includes line wires 43 and 44 and extends to terminal B at front contact *c* of relay 3TR over front contact *a* of relay 3HD or front contact *d* of relay 3S, and to terminal C at front contact *b* of relay 3HD or 3S. The circuit for relay 8LHD includes the left-hand contacts *a* and *b* of relay 8LFS and line wires 41 and 42, and extends to terminals B and C at connectors 53 and 55 over front contacts *a* and *b* of relay 5HD, or at front contacts *d* and *b* of relay 5S. As hereinafter described, when switch 1W is normal relay 8LHD is supplied with current of normal polarity by relay 5HD to condition signal 8LA to indicate proceed, and with current of reverse polarity by relay 5S to condition signal 8LA to indicate caution. When switch 1W is reversed, relay 8LHD conditions signal 8LB to indicate caution when energized by current of either polarity.

It will be seen, therefore, that the single track block extends from the location of signal 2RA through the track sections 1T to 8T, inclusive, to the location of the opposing signal 8LA.

For the block including the passing siding separate line circuits are provided for the two directions for governing the movements of trains over the main track. Although track circuits are provided for sections 10T and 12T of the passing track, these do not control the entering signals, and the control limits for signals 8RB and 2LB which govern movements into the passing track include only the corresponding switch sections 7T and 1T.

Signal 8RA governing train movements over the main track is controlled by a line relay 8RHD, which is normally energized over a circuit extending from its winding over contacts *c* and *d* of relay 9TR, line wires 49 and 50, contacts *c* and *d* of relay 11TR, contacts *a* and *b* of a pole changer relay 2RPC to terminal C, and when switch 1W is normal, to terminal B through the winding of the approach relay 2RAR, connector 13, contact *b* of relay 2LAS, controlled by signals 2LA and 2LB, and contact *b* of relay 1TP. The control limits for signal 8RA therefore normally extend to the opposing head block signal 2LA. As hereinafter described, signal 8RA is controlled over the polar contacts *e* and *f* of relay 8RHD as well as over its neutral contacts *a* and *b* and is conditioned to indicate caution when the next signal 2RA in advance is at stop, and to indicate proceed when signal 2RA indicates caution or proceed. The pole changer relay 8RPC is energized only when signal 8RA indicates proceed, so that signal 6 in the rear does not indicate proceed unless signal 8RA is conditioned to indicate proceed.

Under centralized operation the switch machine ISM for switch 1W is operated by local power supplied over connector 27 in accordance with the position of the code controlled relay 1WS, and when the switch is mechanically locked by the switch machine in its normal or reverse position, a switch indication relay 1NWP or 1RWP is energized over a switch circuit controller contact N or R and a corresponding contact *c* or *d* of relay 1WS and connector 28 or 29. The relays 1NWP and 1RWP thus reflects the po-

sition of the track switch 1W and of its control relay 1WS.

When the switch 1W is reversed, terminal B is connected to the line circuit including wires 49 and 50 at the front contact c of relay 1RWP, so that the control limits for signal 8RA extend only to signal 2RA. Under this condition signals 8RA and 6, in the rear of signal 2RA, may be energized to indicate caution only.

Signal 2LA is controlled like signal 8RA by a line relay 2LHD, which is normally energized over a circuit extending from its winding over contacts a and b of relay 11TR, line wires 47 and 48, contacts a and b of relay 9TR, the pole changer contacts a and b of relay 8LPC to terminal C, and through the winding of relay 8LAR to terminal B at contact c of relay 1RWP or over connector 13 and contacts b of relays 8RAS and 7TP.

Signal 2LA thus does not indicate proceed unless switch 1 is normal and signal 8LA in advance is conditioned to indicate caution or proceed, and signal 3 in the rear does not indicate proceed unless signal 2LA is conditioned to indicate proceed.

The approach relay 2RAR in the circuit for relay 8RHD, and the line relay 2LHD jointly control a slow release relay 2RAP to cause signal 2RA to become lighted when the approach zone comprising sections 9T and 11T is occupied. Similar arrangements involving relays 8LAR, 8RHD and 8LAP are provided for signal 8LA. Signal 8LB or 2RB is lighted when the approach section 10T or 12T, respectively, is occupied, due to the release of the track relay 10TR or 12TR, which has a back contact a in the circuit for the lamp for signal 8LB or 2RB.

Considering now the operation of the system under the emergency condition when all of the connector straps are placed in the left-hand position, it will be seen that the line wires Y1 and Z1 are sectionalized at each signal location by the removal of the connectors from their right-hand terminals. The line wires 41, 43 and 45 and the corresponding sections of the line wire Z1 now provide a system of two wire tandem connected line circuits for energizing relays 6HD, 4HD and 2RHD to control traffic movements from left to right, while the line wires 46, 44 and 42 and the corresponding sections of the line wire Y1 provide a similar system for energizing relays 3HD, 5HD and 8LHD to control traffic movements from right to left, all of these line relays being normally energized.

With the connector straps in their left-hand position, the circuit for relay 6HD extends from the left-hand terminal of its winding over connector 54, back contact c of relay 5S, through the winding of relay 5AR and over contact a of relay 6TR to line wire 41 and thence over contact a of relay 8TR to terminal C at connector 14, and from the right-hand terminal of its winding over connector 57, line wire Z1, connector 72 through relay 8RAR to terminal B at contact a of relay 7TP. The circuit for relay 4HD now extends from its left-hand terminal over connector 39, back contact c of relay 3S, through the winding of relay 3AR and over contact a of relay 4TR to line wire 43 and thence over contact a of relay 5TR, the winding of relay 6AR to terminal C at front contact b of relay 6S or over front contact a of relay 6HD to terminal B at the front contact c of relay 6TR, and from the right-hand terminal of its winding over connector 40, line wire Z1, and connector 59 to terminal B at the front contact c of relay 6TR over front contact d of relay 6S or to terminal C at

front contact b of relay 6HD. The circuit for relay 2RHD now extends from its left-hand terminal over connector 14, contact a of relay 2TR, wire 45, contact a of 8TR and winding of relay 4AR to terminal C at front contact b of relay 4S or over front contact a of relay 4HD to terminal C at connector 33, and from the right-hand terminal of relay 2RHD over connector 12, line wire Z1, connector 36 to terminal B at front contact d of relay 4S or over front contact b of relay 4HD to terminal B at connector 35. It will be seen therefore that signal 6 may indicate stop or caution, signal 4 may indicate caution when relay 6S is energized and may indicate proceed when relay 6HD is energized, and that signal 2RA may indicate caution when relay 4S or 4HD is energized.

It is deemed unnecessary to trace the similar circuits for the opposite direction in detail, further than to point out that relay 3HD is energized in the reverse direction over the circuit extending from terminal B at contact a of relay 1TP to terminal C at connector 14, which circuit includes the line wires 46 and Y1, and that relay 5HD is energized in the normal direction over the circuit extending from terminal B at front contact C of relay 3TR to terminal C at front contact b of relay 3HD, which circuit includes the line wires 44 and Y1, while relay 8LHD is energized in the reverse direction over the circuit extending from terminal B at front contact d of relay 5S or at connector 55 over front contact b of relay 5HD to terminal C at front contact b of relay 5S or at connector 53, which circuit includes line wires 41 and Y1.

Connectors 16 to 25, in Fig. 1A, and connectors 76 to 85, in Fig. 1C, in the left-hand position, complete circuits which permit signals 2RA and 2LA, or signals 2RB and 2LB to indicate caution at the same time.

Under the emergency condition it might happen that two opposing trains would pass the signals 2RA and 2LA at the opposite ends of the single track block at precisely the same time, and it is therefore necessary to insure the provision of adequate stopping distances for both trains. In conventional single track automatic block signaling systems in which the signals stand normally at clear, this is attained by the provision of sufficient distance to stop both trains after they have come into view of the intermediate signals 4 and 5, both of which will indicate stop, but in the centralized traffic control system as shown normally but one direction is set up at a time, consequently this provision is not needed and the distance may be insufficient. That is to say, under centralized operation the distance between signals 4 and 5 may be less than that required for automatic block operation. In short blocks, therefore, connectors such as 33 and 35 are provided in accordance with my invention to limit the indications of the head block signals to stop and caution, while in the longer blocks these connectors may be omitted and the signals arranged to provide their usual three indications under automatic operation.

Considering now the block comprising the main track of the double track stretch, when the connectors are in the left-hand position, relay 2LHD is energized over the circuit extending from terminal B at contact b of relay 7TP over contact c of the track relay 8TR for the approach section 8T and connector 13, contact b of the approach locking relay 8RAS being excluded from the circuit, and relay 8RHD is energized over a similar

circuit including contacts *b* of relay $1TP$ and contact *c* of the track relay $2TR$ for the approach section $2T$, and connector 13 , contact *b* of relay $2LAS$ being excluded. The entering signals $8RA$ and $8LA$ may both be cleared at the same time, in response to the energization of their respective line relays $8RHD$ and $8LHD$, to indicate caution or proceed dependent upon the condition of the pole changer relays $7RPC$ and $8LPC$ controlled by the leaving signals $2RA$ and $8LA$. By placing Fig. 1B at the right of Fig. 1A, it will be seen that signal 3 governing trains approaching the passing tracks from the right stands at caution and that contacts *a* and *b* of relay $2LPC$ and contact *b* of relay $2RAS$ are now excluded from the circuit for relay $3HD$. By placing Fig. 1B at the left of Fig. 1C, it will be seen that signal 6 governing trains approaching the passing tracks from the left also stands at caution and that contacts *a* and *b* of relay $8RPC$ and contact *b* of relay $8LAS$ are now excluded from the circuit for relay $6HD$. Thus under automatic block operation, signals 3 and 6 may be arranged so that both indicate caution when the block is vacant, as is desirable if its length is insufficient to provide adequate stopping distances for opposing high speed trains, as in the case of the opposing signals $2RA$ and $4LA$ hereinbefore discussed, where the situation is similar.

It has been pointed out that under centralized operation relay $8RPC$ is controlled to cause signal 6 to indicate proceed only when the next signal $8RA$ in advance is conditioned to indicate proceed, that is to say, only when the second signal $2RA$ at the right is conditioned to indicate caution or proceed and the opposing signal 3 stands at stop. Similarly, relay $2LPC$ is controlled by the signal mechanism $2LAG$ so that signal 3 indicates proceed only when the second signal $8LA$ to the left is conditioned to indicate caution or proceed and the opposing signal 6 stands at stop. It follows that the stopping distances are provided for trains approaching a passing siding at the same time from opposite directions under automatic block operation equivalent to those provided under centralized operation.

The operation of the local circuits for the head block signals by means of which under centralized operation these signals are interlocked one with another and with the power operated track switches, will now be described; assuming first that the left to right traffic direction is set up with the track switches $1W$ and $7W$ normal, with the track unoccupied, as shown, and that the central office operator has reversed the signal control relay $2RHS$ for clearing signal $2RA$, it being understood that all of the connectors are in their right-hand position as shown.

As shown in Fig. 1A, the approach locking relay $2RAS$ is normally energized over a stick circuit extending from terminal B either at the normal contact *a* of relay $2RHS$ or the reverse contact *a* of relay $2RHS$ and back contact *b* of route relay $2HSP$, and thence over front contact *a* of a signal indication relay $2RGP$ and the contact *a* and winding of relay $2RAS$ to terminal C . The approach locking relay $2LAS$ is normally energized over a similar stick circuit extending to terminal B at contact *a* of the signal control relay $2LHS$.

If a route is available, relays $2RHD$, $1TP$ and $1NWP$ are energized, so that the route relay $2HSP$ picks up in response to the reversal of relay $2RHS$

over a circuit extending from terminal B at the normal contact *c* of relay $2LHS$ over contacts *c* of relays $2RHS$ and $2RHD$, contact *d* of relay $1TP$, contacts *e* of relays $1RWP$ and $1NWP$, through relay $2HSP$ to terminal C . Relay $2HSP$ releases relay $2RAS$ and completes a circuit for mechanism $2RAG$ extending from terminal B at the reverse contact *a* of relay $2RHS$ over front contact *b* of relay $2HSP$, front contact *c* of relay $2LAS$, connector 21 , contact *c* of relay $1TP$, connector 17 , back contact *a* of a time element relay $1TE$, back contact *c* of relay $2RAS$, connector 16 , front contacts *a* of relays $2RHD$ and $1NWP$, through mechanism $2RAG$ over the normal polar contacts *e* and *f* of relay $2RHD$, back contact *a* of relay $1RWP$, front contact *b* of relay $2RHD$, the reverse contact *b* of relay $2RHS$ to terminal C of the normal contact *b* of relay $2LHS$, thereby energizing mechanism $2RAG$ in the normal direction to cause signal $2RA$ to indicate proceed, its signal lamp being lighted by the release of relay $2RAP$ by relays $2LHD$ and $2RAR$ when an approaching train occupies section $9T$ or $11T$. It will be seen that the energization of mechanism $2RAG$ is dependent upon that of relays $2LAS$ and $2LGP$, which check that relay $2LPC$ is released and that the opposing signal mechanisms $2LAG$ and $2LBG$ are at stop, and is also dependent upon the release of relay $2RAS$, which relay holds the opposing signals at stop by opening its front contacts *b* and *c* and locks switch $1W$ by opening its contacts *e* and *f* in the circuit for the switch machine $1SM$, while contact *a* of the time element relay $1TE$ in the signal circuit checks that this relay is fully released.

Relay $1TE$ provides time locking protection against a change in route after a signal has been cleared and accepted by a train, by holding relay $2RAS$ released for a suitable time interval after the signal is manually restored to stop. When signal $2RA$ or $2RB$ is cleared, its indication relay $2RGP$ is released by the circuit controller actuated by the signal mechanism, thereby holding relay $2RAS$ released until the signal is restored to stop. When a train passes the signal and enters section $1T$, the signal is put to stop automatically by the opening of contact *c* of relay $1TP$ in the circuit for the signal mechanism, and the control relay $2RHS$ is then restored to normal by means not shown. In this case relay $2RAS$ picks up at once over a pick-up circuit including contacts *a* of relays $2RHS$ and $2RGP$ and back contact *b* of relay $1TP$. If the signal is restored manually to stop by the operation of relay $2RHS$ when section $1T$ is unoccupied, relay $1TE$ is energized over the circuit from terminal B at the normal contact *a* of relay $2RHS$ which includes back contact *a* of relay $2RAS$ and the front contact *e* of relay $1TP$, and relay $1TE$ closes its contact *c* to pick up relay $2RAS$ at the end of a suitable time interval which is usually from 2 to 6 minutes. The route relay $2HSP$ is controlled over a circuit which being similar to the one over which the signal mechanism is controlled, serves to prevent the release of relay $2RAS$ to render the time locking effective in the event that relay $2RHS$ has been restored to normal because a route is not available.

In case relay $2RHS$ is reversed when switch $1W$ stands reversed, with relays $2RHD$, $1TP$ and $1RWP$ energized, mechanism $2RBG$ may be energized in place of mechanism $2RAG$ to cause signal $2RB$ to indicate caution over a circuit ex-

tending from terminal B at the reverse contact *a* of relay 2RHS over the same path as the circuit for mechanism 2RAG traced above, to contact *a* of relay 1NWP, but since this contact is now in its released position the circuit extends over connector 20 through mechanism 2RBG and over front contact *a* of relay 1RWP, and contacts *b* of relays 2RHD, 2RHS and 2LHS to terminal C.

Considering now the circuits for the opposing signals, if relay 2LHS is reversed when switch 1W is normal and relays 2LHD, 1TP and 1NWP are energized, relay 2HSP is energized by relay 2LHS and releases relay 2LAS, thereby opening the circuits for the opposing signals and for switch machine 1SM and energizing mechanism 2LAG to condition signal 2LA to indicate caution over a circuit which may be traced from the reverse contact *a* of relay 2LHS over front contact *a* of relay 2HSP, connector 18, front contact *c* of relay 2RAS, connector 17, contact *c* of relay 1TP, connector 21, back contact *c* of relay 2LAS, connector 18, front contact *b* of relay 1NWP, contacts *a* and *f* of relay 2LHD, mechanism 2LAG, contacts *e* and *d* of relay 2LHD, back contact *b* of relay 1RWP to terminal C over contacts *b* of relays 2LHS and 2RHS.

If the operator reverses relay 2LHS when switch 1W stands reversed with relays 1TP and 1RWP energized, mechanism 2LBBG will be energized in place of mechanism 2LAG, to cause signal 2LB to indicate caution over the branch circuit extending from back contact *b* of relay 1NWP through mechanism 2LBBG to front contact *b* of relay 1RWP, as will be apparent from the drawing.

The switch machine 1SM is of the dual control type provided with a selector lever 10 which in one position conditions the switch for power operation under control of relay 1WS in which position a contact DS is closed to supply current from terminal B over a switch circuit controller contact N or R, contact *c* or *d* of relay 1WS, and connector 28 or 29 to energize the normal or reverse switch indication relay 1NWP or 1RWP. In a second position the selector lever 10 conditions the switch for hand operation by means not shown, in which position contact DS is open so that relays 1NWP and 1RWP are deenergized. Under centralized operation, therefore, the signal circuits are opened by relays 1NWP and 1RWP so that the signals stand at stop when the switch is conditioned for hand operation, as is desirable because the switch is operated by hand principally for local switching.

I shall now describe the local circuits effective under the emergency condition, assuming that the connector straps occupy their left-hand positions. Connector 27 now disconnects terminal B from the circuit for supplying power to the switch machine 1SM and connects terminal B directly to the circuits for relays 1NWP and 1RWP, while connectors 28 and 29 bridge the contacts *c* and *d* of relay 1WS in the indication relay circuits, so that relay 1NWP or 1RWP is energized and indicates the position of the switch as reflected by contacts N and R, irrespective of the position of relay 1WS or of lever 10, so as to enable the signals to be cleared even though the track switch is conditioned for hand operation. Furthermore, under the emergency condition the signal mechanisms 2RAG and 2LAG may both be energized at the same time in response to the energization of their respective line relays 10

when switch 1W is normal, and mechanisms 2RBG and 2LBBG may be both energized at the same time when switch 1W is reversed.

When the connector straps are in the left-hand position terminal B at connector 21 supplies current over contact *c* of relay 1TP to connector 17 and thence to connectors 16 and 18. Mechanism 2RAG is energized over connector 16, front contacts *a* of relays 2RHD and 1NWP, and contacts *e* and *f* of relay 2RHD, and over back contact *a* of relay 1RWP and front contact *b* of relay 2RHD as already traced, and thence to terminal C at connector 24, so that signal 2RA may be cleared automatically regardless of the positions of relays 2RHS and 2RAS, or of relays 2LAS and 2LAS governed by the opposing signals. Mechanism 2RAG when energized releases relay 2RGP, which in turn releases relay 2RAS. The circuit for mechanism 2LAG extends from connector 18 over front contact *b* of relay 1NWP and includes contacts *a*, *d*, *e* and *f* of relay 2LHD and back contact *b* of relay 1RWP, and extends to terminal C at connector 23. If switch 1W is reversed, relay 1RWP is energized and mechanism 2LBBG is energized over the branch circuit including front contact *b* of relay 1RWP and back contact *b* of relay 1NWP. It follows that signal 2LA or 2LB may be cleared regardless of the position of relays 2LHS or 2LAS, or of relays 2RAS and 2RAS.

The circuit for mechanism 2RBG is differently arranged so as to provide time locking protection for movements out of the side track in accordance with a feature of my invention. When the connectors are in the left-hand position relay 2RAS is controlled by mechanism 2RAG only, due to the connections from terminal B at connectors 22 and 25 to the circuits for relays 2RGP and 2RAS. The circuit for mechanism 2RBG now extends from terminal B at connector 21 over contact *c* of relay 1TP to connectors 17 and 16 and thence over front contact *a* of relay 2RHD, back contact *a* of relay 1NWP, connector 19, front contact *c* of relay 2RAS, back contact *a* of relay 1TE, connector 20, mechanism 2RBG, front contact *a* of relay 1RWP, front contact *b* of relay 2RHD to terminal C at connector 24. When the connectors are in their left-hand position, with signals 2RA and 2LA energized, if switch 1W is operated by hand to the reverse position for a movement out of the side track, relay 1NWP releases, restoring signals 2RA and 2LA to stop, but relay 2RAS remains released for the duration of the time locking period imposed by relay 1TE. Relay 2RGP becomes energized over connector 25 and the circuit controller for mechanism 2RAG when signal 2RA returns to its stop position, completing a circuit from terminal B at connector 22 over front contact *a* of relay 2RGP and back contact *a* of relay 2RAS and contact *e* of relay 1TP to energize the time element 1TE. The branch of the circuit for relay 1TE which includes back contact *a* of relay 2LAS is now open at connector 26, and consequently is ineffective. Relay 1TE energizes relay 2RAS after the lapse of a suitable time interval, which relay is then held energized over its stick circuit and releases relay 1TE. The closing of back contact *a* of relay 1TE and of front contact *c* of relay 2RAS completes the circuit for mechanism 2RBG. The display of a caution indication by signal 2RB is thereby delayed following the reversal of switch 1W, for a time sufficient to enable a train approaching signal 2RA either to stop before passing the signal if

its speed is low, or to enter section 1T and thereby prevent the clearing of signal 2RB if its speed is high.

Referring now to Fig. 1C, it will be seen that the circuits for signals 8LA and 8LB are similar to those for signals 2RA and 2RB, while those for signals 8RA and 8RB are similar to those for signals 2LA and 2LB described above, and that the connector straps 71 to 89, inclusive, correspond in function to the straps 11 to 29, inclusive. A detailed explanation of these circuits is therefore deemed unnecessary.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In a centralized traffic controlling system for railroads, a stretch of single track railway comprising a traffic block, signals for governing traffic movements in opposite directions into said block, a system of reversible line circuits employing two line wires for controlling said signals in accordance with traffic conditions in said block, a code communication system employing two other line wires for controlling the direction of energization of said line circuit system and for selectively controlling said signals, a system of adjustable connectors at each signal location which in one position are included in said line circuits, and means including said connectors in a second position for establishing other line circuits for automatically clearing the signals for both directions at the same time in accordance with traffic conditions each of said other line circuits including one or the other of the line wires of said communication system and one or the other of the line wires of said reversible line circuit system.

2. In a centralized traffic controlling system for railroads, a stretch of single track railway comprising a traffic block, signals for governing traffic movements in opposite directions into said block, a system of reversible line circuits employing two line wires for controlling said signals in accordance with traffic conditions in said block, a code communication system employing two other line wires for controlling the direction of energization of said line circuit system and for selectively controlling said signals, a system of adjustable connectors at each signal location which in one position are included in said line circuits, means including said connectors in a second position for establishing a four wire line circuit system employing the two line wires of said reversible line circuit system and the two line wires of said communication system, and means including said four wire line circuit system for automatically clearing the signals for both directions at the same time in accordance with traffic conditions in said stretch.

3. In a centralized traffic control system for railroads, a stretch of single track railway comprising a traffic block, head block signals adapted to indicate proceed or caution for governing traffic movements into said block, intermediate signals for governing traffic movements at spaced locations within the block, a system of tandem connected polarized line circuits controlled in accordance with traffic conditions in said block for controlling said signals, means including

manually adjustable connectors at each signal location which in one position render said circuits effective to energize the signals for only one direction at a time and in a second position render the circuits effective to energize the signals for both directions at the same time, and means including the connectors at intermediate locations in their second position for reversing the polarity of the current supplied to the line circuits for the head block signals to prevent either head block signal from indicating proceed when both are energized.

4. In combination with a stretch of railway track, a switch section in said stretch including a power operated track switch, signals for governing traffic movements into said switch section in opposite directions, line relays for controlling said signals in accordance with traffic conditions in said stretch, manually controllable signal control relays for controlling the clearing of the signals, a manually controllable switch control relay for controlling the track switch, approach locking relays controlled by the signals each of which in one position is normally effective to prevent the clearing of the associated signal and in another position to prevent the operation of the track switch or the clearing of an opposing signal, indication relays controlled by the track switch arranged to be energized normally only when the switch occupies a position corresponding to that of its control relay, a group of manually adjustable connectors, circuits established by said connectors in either of two positions for controlling said signals in accordance with the condition of their line relays and of said switch indication relays, the circuits established by said connectors in one position only being dependent upon the condition of said signal control relays and of said approach locking relays, and means including said connectors in said second position for rendering the energization of the switch indication relays dependent upon the position of the track switch irrespective of the condition of said switch control relay.

5. In combination with a stretch of railway track including a track switch, indication relays for indicating the position of the switch, signals for governing traffic movements over the switch, energizing circuits for the signals including front contacts of said indication relays and a manually controllable contact and also including contacts reflecting traffic conditions in the stretch, a manually controllable switch control relay, a dual-control switch machine having a selector lever which in one position conditions the track switch for power operation by its control relay and in a second position conditions the switch for hand operation, circuits for selectively energizing said indication relays including contacts indicating the position of the switch and contacts closed by the switch control relay in a position corresponding to that of the track switch, said circuits also including a contact closed by the selector lever in said one position, a group of adjustable connectors included in the circuits for said signals and for said indication relays, and means including said connectors for rendering said control relays ineffective to control the switch and signals and for completing circuits for energizing said indication relays in accordance with the position of the track switch regardless of the position of the switch control relay or of said selector lever.

6. In combination with a stretch of railway track including a track switch, a first and a

second signal for governing traffic movements in a trailing direction over the switch in its normal and reverse positions, respectively, energizing circuits for said signals controlled in accordance with traffic conditions in the stretch and the position of the track switch, an approach locking relay, a dual control switch machine having a selector lever which in one position conditions the switch for power operation and in a second position conditions the switch for hand operation, a group of adjustable connectors included in the circuits for said signals and said relay, pick-up and stick circuits for said approach locking relay including a contact which when closed indicates that the first signal is at stop and when said connectors are in one position includes also a contact which when closed indicates that the second signal is at stop, said pick-up circuit also including a time controlled contact for delaying the energization of the approach locking relay for a time after the controlling signal is put to stop, a circuit for effecting the power operation of said switch machine including one of said connectors and a front contact of said approach locking relay and arranged to be supplied with

5
